Inventor:
Edwin R. Probert,

By John Elias Jones,
Attorney.

UNITED STATES PATENT OFFICE.

EDWIN R. PROBERT, OF COVINGTON, KENTUCKY.

SHEET-METAL ROOFING.

1,406,082.

Specification of Letters Patent.

Patented Feb. 7, 1922.

Application filed May 2, 1919. Serial No. 294,340.

To all whom it may concern:

Be it known that I, EDWIN R. PROBERT, a citizen of the United States of America, and a resident of Covington, in the county of 5 Kenton and State of Kentucky, have invented a certain new and useful Improvement in Sheet-Metal Roofings, of which the following is a specification.

This invention relates to sheet-metal roofing having crimped longitudinal edges that are adapted to register and overlap in making seams or joints and then nails driven through such lapped crimps into the sheathing beneath for securely fastening the roofing into place for use; and the object of my improvement herein is to provide an overlapped crimp-joint that will require practically no more material nor more labor or machinery in making it than the plain inverted-V-shape crimp-joint in common use and which latter, common form is always subject to more or less capillary leakage and the fastening-nails are driven through the pointed apexes of the crimps in a most inconvenient and frequently injurious manner, especially when the points of the nails slip from said apexes and accidentally penetrate the main sheet-portion below to cause undue leakage, or they must otherwise be driven 30 into the steep sloping sides of the crimps, that would induce more or less leakage.

The said object is best accomplished by me in providing an overlapping-crimp joint of peculiar structure, whose under-crimp 35 comprises an inclined bracing-member that develops into an integral, downturned or vertical extension or supporting-member and that develops thence into a horizontal, lateral fastening-flange or foot-member, and 40 whose overlapping or topping crimp comprises an inclined outer-member that coincides with the said inclined bracing-member of the under-crimp and develops into an integral shallow downturned or vertical extension 45 and from thence into a short slightly sloped nailing ledge or wing-member, which latter has, also, a still further and final, outwardly-sloping downward-extension or brace-member that thence passes or extends 50 onward into the next adjoining sheet.

Other incidental features and the advantages of my peculiar form of roofing herein will be fully hereinafter described in connection with the accompanying sheet of drawings, in which,—

Figure 1 is a fragmentary perspective

view showing one form of my improved joint;

Figure 2, a transverse section of Fig. 1 showing the manner in which a hook-headed nail is driven into fastening-place; and

Figure 3, a fragmentary perspective view of the joint, showing a modification and including a fastening-nail in position ready for driving into the joint. 65

In all these views, I show simply the joints of contiguous sheets, the latter being in but fragmentary portions and indicated by the numerals 8 and 9, and the joint being composed of an under-crimp on the sheet 8 and 70 an overlapping or top crimp on the sheet 9.

In Figs. 1 and 2, the under-crimp is composed of a plane upwardly inclined or slanting member 10, an integral, downturned, somewhat highly slanting member 11 and an 75 integral horizontal base or foot-member 12 that extends laterally from the lower edge of member 11, and the upper or overlapping crimp on the sheet 9 is composed of an upright but somewhat highly-slanting but 80 somewhat curtailed or shallow member 13 that develops into an intermediate approximately-horizontal member 14 that thence develops into an upper capping arc-shape member 15 and which, in turn, develops into a 85 downturned slanting-member 16, the latter coinciding with the slanting-member 10 that it laps in use and with its lower edge somewhat above the angle 17 made in the sheet 8 in producing the upwardly-slanting member 90 10, such curtailing of the member 16 above the angle 17 being intended to minimize any capillary tendency of the water beneath the lapped members 10 and 16 and to seep into the other members of the joint beyond. 95

The hook-headed nail 18, shown in Fig. 2, is used to secure the joint in place on the sheathing 19, the point of the nail entering the elevated, approximately-horizontal member 14 of the upper-crimp, as best shown in 100 Fig. 3, at an inclination so that after it penetrates that member 14 it continues onward (as indicated by the dotted arrow 20) into the angle 21 that connects the foot-member 12 with the somewhat highly-slanting member 11 of the under-crimp, and then it finally continues onward into the sheathing, and the said hook-head conforming to and firmly engaging with the slightly-curved apex of the lapped joint when driving the nail home. 105

The slope of the ledge member 14 is sufficient to readily drain any water falling

thereon, and the chamber beneath forms an air-space as well as an ample passage-way to offset any moisture that might seep into the joint, and thereby keep the joint dry.

5 The chamber or passage-way beneath the under-crimp members 10 and 11 forms a dry air-space proof against leakage, especially when no nails are driven into the lapped apex of the joint above. The said 10 slightly sloping and somewhat broad, plane-member or ledge 14 forms a very desirable, convenient and substantial rest or foot-hold for the nail-points that may be easily positioned and driven therethrough without 15 slipping or shifting when laying the roofing, and it, therefore, forms an important feature of my invention herein. Besides, it requires little or no additional material to produce the angled-member composed of the members 13 and 14 over the amount of material 20 for the ordinary inverted-V plane-faced crimp joint-members, and the cost of manufacture is not increased to any appreciable extent either, as will be clearly obvious without 25 going into any minute explanatory detail.

It will be seen in all three views of the drawing, that the outer edge of the foot-member 12 does not extend clear up to the 30 angle 22 of the lapping-sheet 9 and its first joint-member 13, thus saving in the undue use of material.

The approximately-perpendicular members 11 and 13 of the joint present firm, 35 stiff supports or pillars to facilitate the proper driving of the nails into the joint to materially reinforce the joint and thereby obviate collapse or spreading thereof in laying the roof and in its after use. Thus no 40 cleats are necessary in my form of joint herein when securing it in place on the sheathing.

To still further obviate any tendency to capillary leakage into the joint, I show in the modified form, Fig. 3, an angular, outward bulge or bend 23 in the lapping-member 16, that provides an air-space and passage-way 24 for any moisture that might seep upwardly from the lower, elevated edge of the member 16, and thus an effective barrier is provided against said capillary leakage into the lapped apex above or beyond, the space or passage-way 24 being of ample capacity to drain any leakage entering under the said lower edge of the member 16, and with little added material in said member 16 for the said bulge being required in its manufacture.

The flat-headed ordinary nail 28 seen in Figure 3 can and will, of course, be used

in the laying of this roofing the same as the 60 hook-headed nail shown in Figure 2 and above referred to.

I claim:—

1. In sheet-metal roofing, a joint for contiguous sheets comprising an under-crimp 65 formed along one sheet and having an upwardly-slanting member, an integral approximately-perpendicular supporting-member and a horizontal plane foot-member extending laterally from the said supporting-member, and an upper or lapping single crimp formed along the other or next sheet and having in its structure a shallow upwardly-slanting member, an elevated approximately-horizontal nail-receiving member 70 extending laterally from the said shallow upwardly-slanting member toward the said supporting-member of the first-named crimp-structure and a shallow slightly inclined member leading upwardly from said nail-receiving member to a crown or apex-member and an integral outer downwardly-inclined member extending from said crown or apex-member and adapted to align with and lap upon the first-named slanting member 75 of the first-named crimp-structure, and fastening-nails adapted to be driven through the said elevated widely-spaced and approximately-horizontal member of the single upper crimp structure, thence downward 80 through the said horizontal plane foot-member of the lower-crimp and finally into the sheathing beneath.

2. In sheet-metal roofing, a joint for contiguous sheets comprising an under-crimp 95 formed along one sheet and having an upwardly-slanting member, an integral approximately-perpendicular supporting-member, and a foot-member, an upper crimp formed along the other sheet and having an 100 upwardly-inclined shallow member, an integral intermediate approximately-horizontal plane nail-receiving member, a shallow vertical member leading from the said intermediate approximately-horizontal member to an apex-member, an integral, outer, downwardly-inclined member adapted to lap upon the first-named slanting member of the under-crimp and having an outward bulge 105 formed longitudinally in the last-named inclined lapping-member, and fastening-nails adapted to be driven through the said intermediate approximately-horizontal member of the upper-crimp and the foot-member 110 of the under-crimp into the sheathing beneath.

EDWIN R. PROBERT.
